US00D626810S

(12) **United States Design Patent**
Steineckert et al.

(10) **Patent No.:** US D626,810 S
(45) **Date of Patent:** ** Nov. 9, 2010

(54) **HAND TOOL**

(75) Inventors: **Jennefer Ruth Steineckert**, Portland, OR (US); **Benjamin C. Rivera**, Lake Oswego, OR (US)

(73) Assignee: **Leatherman Tool Group, Inc.**, Portland, OR (US)

(**) Term: **14 Years**

(21) Appl. No.: **29/346,849**

(22) Filed: **Nov. 6, 2009**

(51) **LOC (9) Cl.** 08-05

(52) **U.S. Cl.** D8/55; D8/105

(58) **Field of Classification Search** D8/1, D8/4, 5, 14, 20, 51–56, 58, 105–107; 7/128, 7/168, 158, 165, 125, 138; 81/177.4, 440, 81/427.5, 300, 418–424, 424.5, 426, 426.5, 81/427; 30/158–161, 236, 262

See application file for complete search history.

(57) **CLAIM**

The ornamental design for a hand tool, as shown and described.

DESCRIPTION

FIG. 1 is a perspective view of a hand tool, shown in an open configuration, according to my new design;

FIG. 2 is another perspective view thereof;

FIG. 3 is a left side elevation view thereof;

FIG. 4 is a right side elevation view thereof;

FIG. 5 is a top plan view thereof;

FIG. 6 is a bottom plan view thereto;

FIG. 7 is a front elevation view thereof;

FIG. 8 is a rear elevation view thereof;

FIG. 9 is a perspective view of a hand tool, shown in a closed configuration, according to my new design;

FIG. 10 is another perspective view thereof;

FIG. 11 is a left side elevation view thereof;

FIG. 12 is a right side elevation view thereof;

FIG. 13 is a top plan view thereof;

FIG. 14 is a bottom plan view thereto;

FIG. 15 is a front elevation view thereof; and,

FIG. 16 is a rear elevation view thereof.

The broken lines immediately adjacent the shaded areas represent bounds of the claimed design and environment while all other broken lines are directed to environment and are for illustrative purposes only. The broken lines form no part of the claimed design.
